UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

WATER TUBE.

Application filed December 8, 1925. Serial No. 74,040.

This invention relates to rock drills of the hammer type but more particularly to an improved connection between the liquid conducting tube and the back head of the 5 rock drill, including an improved means for removing the liquid conducting tube in the event of breakage thereto or for any other reason. Most rock drills of the hammer type employ a tube which extends through the machine and a short distance into the drill steel for conveying liquid under pressure to the 10 hollow bore of the drill steel for the purpose of cleansing the drilled hole. These tubes frequently become so damaged that they are 15 of no further use, which necessitates the removal of the damaged tube and substitution of a new tube. Heretofore much trouble and annoyance has been occasioned in the removal of the damaged tubes. It has also 20 been a difficult problem to obtain an efficient fluid-tight connection between the liquid conducting tube and the back head and frequently the liquid, usually water, enters the working parts of the machine and washes 25 away the lubricant. This, of course, is disadvantageous and tends to shorten the life of the machine. By means of my invention the above difficulties are overcome, as an efficient and reliable fluid-tight connection is 30 obtained between the liquid conducting tube and the back head of the machine, while at the same time by means of a readily accessible plug the liquid conducting tube and the associated parts may be conveniently 35 removed from the back head of the machine and in the replacement of a new tube the necessary parts to be replaced, besides the tube, would only be inexpensive iron washers.

40 One object of my invention therefore is to enable a liquid conducting tube to be attached to the back end of a rock drill in a simple and improved manner so that an efficient fluid-tight connection therebetween 45 is produced without the use of material such as rubber, which is subject to deterioration.

Further objects of the invention will hereinafter appear and the invention consists in certain features of construction and the combination of elements described in the following specification, described in the appended claims and shown in the drawings, in which,

55 Figure 1 is a side elevation of a rock drill of the hammer type showing my invention

in horizontal section along with so much of the rock drill as is necessary to illustrate the application of the invention to a rock drill,

Figure 2 is an enlarged detailed horizontal section of the connection between the liquid conducting tube and the back head shown in Figure 1, and

Figure 3 is a detailed view of the threaded plug which is one of the elements of my 65 invention.

Referring to the drawings, the back head A, the cylinder B and the front head C of a rock drill of the hammer type are shown in proper relation each to each. A rock drill 70 steel D is shown partly entering the rock face E and it is desired to feed fluid under pressure through the bore F in the rock drill to the drill hole G. In order to do this, a fluid conveying tube H extends from the back head A of the rock drill through the cylinder B and the hammer piston (not shown) into the shank of the rock drill steel D. From the valve J regulating the supply of pressure fluid is a passage K leading into a cylindrical recess L in the back head. The fluid conveying tube also extends into this cylindrical recess L, there being a slidably fit between the tube H and the walls of the bore O in the back head, 80 while a flange P is provided on the end of said fluid conveying tube. At the front end of the cylindrical recess L is a thin washer Q preferably of some soft metal which is adapted to fit around the tube H and to 85 have the same diameter as the recess L. Against this is placed a cylindrical metallic body R with a bore of the same diameter as the tube H and of sufficient thickness to 90 guide and hold the tube H rigidly. The front face of this metal body has been concentrically grooved so that it will bite the surface of the washer Q when pressure is applied, while a circular recess has been cut in its rear face to receive the flange P of the fluid conveying tube H. Behind this metallic body R is a third thin metallic washer S 95 adapted to lie over and upon the flange P of the tube H while having a hole in its center corresponding to the bore in the fluid conveying tube H. These parts are held in fixed relation to each other by means of the externally threaded plug T which is adapted to be screwed into the recess L against the rear metallic washer S. The rearward half 100

105

110

of this plug T protrudes from the recess L while a bore U is provided through the center of the plug T to correspond with the bore in the fluid conveying tube H. The 5 rearward portion of this plug T has been relieved or cut down on two sides as is shown clearly in Figure 3, while at the same time sufficient threaded surface is provided to receive a recessed cap V which is screwed 10 down over the plug T until it abuts against the rearward face of the back head and thereby serves to lock the back head plug T and to seal the recess L. As a result of the relieved or cut down portions of the 15 plug, a clear passage is provided for liquid to be directed by the valve J through the passage K, to the cavity W in the head of the cap V, and thence through the bore U of the plug T, and the fluid conveying tube 20 H, to the bore of the rock drill steel F to the drill hole. In the assembly of this device it will be seen that the plug T can be easily screwed into the recess L and that pressure will thereby be applied to the 25 washers L and Q and the intermediate metallic body R and that as a result the castellations or grooves in its forward face will bite into the washer Q and spread it against the cylindrical walls of the recess P, with 30 a result that a water tight connection will be formed for the liquid conveying tube H. In order to remove the tube all that is necessary is to unscrew the cap V and the plug T, whereupon the tube H can easily be 35 tractored.

I claim:

1. In a rock drill, the combination of a back head, a cylindrical recess in said back head, a passage communicating with said recess into which liquid under pressure is 40 adapted to be introduced, a liquid conducting tube co-axial with the rock drill and extending into said recess, a flange on the end of said tube, a front metallic washer 45 of the same diameter as the said cylindrical recess adapted to fit around said tube within the recess, an intermediate metallic cylindrical body in said recess of the same diameter as the said recess adapted to fit slidably 50 around said tube and having an indentation

on the rear face thereof to embrace the flange on said tube, a rear washer of the same diameter as the recess and adapted to overlap the said flange on the tube and the rear face of the said metallic body, an externally threaded hollow plug adapted to be screwed into the said cylindrical recess and adapted to abut against the rear washer for holding the rear washer against the said metallic body, a cap adapted to be screwed over the said plug, and means for conveying liquid from the said recess into the bore of the said hollow plug.

2. In a rock drill, the combination of a back head, a cylindrical recess in said back head, a passage in communication with said recess into which liquid under pressure is adapted to be introduced, a liquid conducting tube coaxial with the rock drill and extending slidably into said recess for a substantial distance, a flange on the end of said tube within the recess, a soft metallic washer adapted to fit around the said tube and in the bore of said recess, a cylindrical body or washer likewise adapted to fit around the 75 said tube and within the bore of said recess, the said body having a concentrically grooved front face for contact with the said front washer and having a recess in its rear face to receive the flange on the fluid conveying tube, a rear washer of the same diameter as the said recess and having a central hole to correspond with the bore of the said tube, adapted to lie over and hold the said flange on the rear of the said tube 80 against said cylindrical body, an externally threaded hollow plug screwed partly into said recess and abutting against the said back washer having a bore corresponding to the hole in said washer, a recessed cap 85 adapted to be screwed on the said plug to lock the plug and seal the back head, and a relieved portion on said plug to allow liquid to be conveyed from the said recess in the back head to the bore in said plug 90 and thence to the said fluid conveying tube.

In testimony whereof I have signed this specification.

CHARLES C. HANSEN.
